UNITED STATES PATENT OFFICE.

SILAS C. BLAUVELT, OF BLAUVELTVILLE, NEW YORK.

IMPROVEMENT IN STEP-LADDERS.

Specification forming part of Letters Patent No. **175,016**, dated March 21, 1876; application filed February 28, 1876.

To all whom it may concern:

Be it known that I, SILAS C. BLAUVELT, of Blauveltville, Rockland county, New York, have invented a new and Improved Step-Ladder, of which the following is a specification:

Figure 1 is a vertical section of my improved step-ladder arranged for use, and showing in dotted lines its position when arranged as a ladder; and Fig. 2 is a side view of the same folded for storage or transportation.

Similar letters of reference indicate corresponding parts.

The object of this invention is to furnish an improved step-ladder which shall be so constructed that it may be readily arranged for use as a step-ladder or as an ordinary ladder, and may be folded together for storage and transportation, and, when adjusted for either purpose, will be held securely in place, and which shall be simple in construction and convenient and reliable in use.

The invention consists in the blocks or plates provided with the semicircular rear ends, and the notches, the pin, and the slot, when used in connection with the pivot and the parts of the step-ladder, as hereinafter fully described.

The ladder is made in two parts, A B, hinged to each other at their upper ends, and which are provided with steps or rounds in the usual way.

To the upper ends of the side bars of the

front part A are attached blocks or plates C, the rear ends of which are rounded off or made semicircular, and are pivoted to the upper ends of the side bars of the rear part B by pivots D, which pass through holes in the plates or blocks C, and through short slots b¹ in the side bars of the part B.

To the side bars of the part B, in line with the slot b¹, and at such a distance below it as to move along the curved edge of the block or plate C when the pivot D is in the upper end of said slot b¹, is attached a pin, b².

In the curved edge of the blocks or plates C are formed three notches, C', in such position as to receive the pin b² and lock the parts A B together when arranged for use as a step-ladder and as a ladder, and when folded, as shown in Figs. 1 and 2.

Having thus described my invention, I claim as new and desire to secure by Letters Patent—

The blocks or plates C, provided with the semicircular rear ends and the notches C', the pin b², and the slot b¹, when used in connection with the pivot D and the parts A B of a step-ladder, substantially as herein shown and described.

SILAS CALVIN BLAUVELT.
